UNITED STATES PATENT OFFICE.

ANDREW H. REEDER, OF STONEGA, VIRGINIA.

COKE-DRAWER.

980,004.

Specification of Letters Patent. Patented Dec. 27, 1910.

Application filed November 17, 1909. Serial No. 528,521.

To all whom it may concern:

Be it known that I, ANDREW H. REEDER, a citizen of the United States, residing at Stonega, in the county of Wise and State 5 of Virginia, have invented new and useful Improvements in Coke-Drawers, of which the following is a specification.

The present invention is an improvement in machinery for "pulling" or "discharging" coke from coke ovens, more generally known as "coke drawers," and its principal object, broadly stated, comprehends the production of a highly efficient and readily-operated machine constructed in such a 15 manner that the "beam" or that element which corresponds thereto, is capable not only of being raised and lowered bodily, but also of being swung in both a horizontal and a vertical plane. There is thus produced, in effect, a universal mounting of the beam which enables the shovel or other tool to reach all portions of the oven.

Furthermore, the invention contemplates the production of a coke drawer wherein the 25 reciprocal movement of the beam and the various adjustments thereof, are effected by means of an operating fluid, suitably supplied to the several operating mechanisms, the supply being controlled by specially constructed devices.

The invention still further resides in the employment of a specially constructed mechanism by means of which the bodily movement of the machine along the battery of 35 ovens is obtained, such mechanism, like the afore-mentioned adjusting mechanisms, being fluid-operated.

Finally, the invention comprehends the production and employment of a special 40 form of shovel, the parts of which bear a definite relation to each other and operate in a particular manner.

A structural embodiment of the invention is illustrated in the accompanying drawings 45 whereof—

Figure 1 is an end elevation of the complete machine showing the beam in its projected position, with the shovel within one of the ovens, the latter appearing in section. 50 Fig. 2 is an enlarged plan view of the machine parts thereof being broken away. Fig. 3 is an enlarged side elevation. Fig. 4 is a similar end view with parts in section. Fig. 4^a is a fragmental side elevation of the

rear end of the main cylinder in which the beam operates. Fig. 5 is a plan view of the combined air and water tank. Fig. 6 is a plan view of the shovel carried by the beam. Fig. 7, 8 and 9 are side elevations showing the three positions assumed by the parts of the shovel when the latter is operated. Fig. 10 is a front elevation of Fig. 7. Fig. 11 is an enlarged fragmental view illustrating the connection between the devices for operating the main valve and one of the valves which control the swinging movement of the beam. Fig. 12 is a vertical section taken transversely of Fig. 11. Figs. 13 and 14 are detail perspective views of tools which may be substituted for the shovel.

Reference being had to the drawings, and to the characters marked thereon, A designates in a general manner one of a battery of coke ovens; B the track arranged in front of said ovens; and C the carriage which travels along the track and supports the various operating mechanisms of the drawer. These mechanisms comprise the beam and beam-cylinder designated by the character D, the vertical-rocking mechanism E, the horizontal-swinging mechanism F, the lifting-jack G, and the traction mechanism H. The coke ovens are of the ordinary construction and require, therefore, no extended description. The track B parallels these ovens, as is customary. The carriage C is in the form of an ordinary four-wheel truck, and its platform 1 is supported upon the axles 2 and 3, as shown best in Figs. 3 and 4.

The mechanism D comprises a cylinder 4 supported centrally of its length by horizontal trunnions 5, journaled in bearings 6 with which a casting 7 is provided. This casting is formed or otherwise rigidly mounted upon the upper end of a tubular metal element 8 which acts as the cylinder of the lifting-jack G, hereinafter described, and is formed at its lower end with a continuous lateral flange 9, said flange serving to support a turn-table 10. Within cylinder 4 there are arranged main and supplemental pistons 11 and 12. The rod portion 13 of piston 11 forms the beam of the machine and, as such, is designed to carry at its outer end 100 a shovel or other tool. It is hollow or tubular, as shown in Fig. 4, and receives within its bore the supplemental piston 12 which is

stationary and has the rear end of its rod portion 14 rigidly secured to the rear head of cylinder 4. The bores of the two rods 13 and 14 are continued through the piston heads 15 and 16.

The beam, or more properly, the main piston is operated by fluid pressure admitted on opposite sides of its head 15 by means of a pair of pipes 17 and 18. The present, or 10 inner ends of these pipes open into a main valve chest 19, while their outer ends are received in ports 20 and 21 formed adjacent the opposite ends of the cylinder. The operating fluid, which may be either compressed 15 air or steam, preferably the former, enters the valve chest through a pipe 22 connected by a short length of rubber hose 23 with a pipe 24 to which, in turn, is connected a second hose pipe 25. Pipe 25 is connected to a 20 pipe 26 mounted on the platform 1 of the carriage and designed for connection by means of a removable hose pipe 27 with the branch 28 of a continuous supply pipe or main 29 located near the top of the battery 25 of ovens, there being, as will be understood, a separate branch pipe for each oven. There is also located in front of each oven a stand-pipe 30 which communicates with an underground water-main (not shown).

30 Within the valve-chest 19 is arranged a sliding D-valve 31 operated manually by a rod 32 having at the outer end thereof a handle 33. This valve is shown in its position of rest in Fig. 4, wherein both of the 35 inlet passages 35 and 36 formed in the bottom wall of the chest are closed, the exhaust passage 34 being continuously open. The main inlet pipe 26 is provided at its outer end with a valve 37 which controls the flow 40 of the operating fluid into said pipe when the latter is connected up with one of the branch pipes 28. Valve 31 controls the passage of the fluid from the chest into the interior of the main cylinder 4, upon one side or 45 the other of the main piston head 15, and hence by reciprocating the valve rod 32, a similar movement will be imparted to the beam or main piston.

The mechanism E for swinging or tilting 50 the beam cylinder 4 in a vertical plane comprises essentially an upright cylinder 38, having a trunnion or hinge-connection 39 at its lower end with the turn-table 10 and having its piston rod 40 pivotally connected 55 at its upper end, as indicated by the numeral 41, to a collar 42 secured to said beam cylinder. The movement of the piston rod 40 is controlled by a slide valve 43 located within a valve chest 44 attached to cylinder 60 38, to which chest the operating fluid is supplied through a hose pipe 45 communicating with the supply pipe 22. Valve 43 is connected by a link 46 to an arm 47 secured to a shaft 48 journaled in brackets 49 and 50 fastened to cylinder 38. Shaft 48 carries a

second arm 51 which is arranged at an angle to arm 47 and is connected by a rod 52 with the adjacent arm of an angle lever 53 fulcrumed upon one of the trunnions 5. Lever 53 has its other arm connected by a link 54 to a curved lever arm 55 formed at its upper end with a lateral sleeve 56, the ends of link 54 being universally jointed to the above mentioned arms. Sleeve 56 is arranged between two spaced brackets 57 integrally connected together at their lower ends and clamped to cylinder 4 by U-bolts 58, the space between said brackets being slightly greater than the length of said sleeve, so as to permit a limited movement of the latter in either direction (see Fig. 11). This sleeve is fitted upon an elongated sleeve 59 rigidly secured in any desired manner to valve rod 32 and having its ends projecting loosely through openings formed in brackets 57, owing to which construction it will be understood that said valve rod is thus supported by the brackets. Sleeve 59 has formed in its upper surface a longitudinal key-way 60 which extends almost the entire length thereof, and receives the reduced lower ends of a pair of screws 61 tapped into sleeve 56. It is therefore apparent that both valves 31 and 43 are operable by a single element, namely, rod 32, an endwise movement of said rod serving to shift valve 31, while a rotary movement will raise or lower valve 43. With reference to the operation of the latter valve, it may be stated that a rocking movement of lever 55 (effected by turning or rotating rod 32) will rock angle lever 53 through its link connection 54 therewith; lever 53, on being rocked, will rock the angle lever formed by shaft 48 and its arms 51 and 47, the second arm 55 being connected by link 46 to said valve 43.

The mechanism F for imparting a lateral or horizontal swinging movement to the beam and beam cylinder comprises a horizontal cylinder 62 supported intermediate 110 its ends by a U-shaped casting or bracket 63, provided at the upper ends of its legs with bearings for the horizontal trunnions 64 secured to said cylinder. The base portion of this bracket 63 has an integral bearing sleeve or boss 65 which is received in a seat 66 formed in a casting 67 carried by the platform 1. This bearing sleeve or boss is also provided with a depending pin 68 extending through openings in the casting and bracket and having a nut 69 threaded on the lower end thereof. Hence, it will be apparent that the cylinder is capable of rocking movement in both a vertical and a horizontal plane, so as to accommodate itself to the 115 various movements of the beam cylinder.

The piston 70 movable within cylinder 62, has the outer end of its rod 71 connected to a radial extension 72 formed upon the turn-table 10. The fluid for operating said piston 130

is admitted into cylinder 62 from a valve chest 73, mounted thereon, fluid being supplied to said chest by a hose pipe 74 which opens at one end thereinto and at the other end into a lateral branch 75 of pipe 26. Chest 73 is formed with a pair of inlet passages 76 and 77, and an exhaust passage 78, the openings to these passages being controlled by a slide valve 79 operated by a rod 80. Communication is had between passage 77 and the cylinder 62 by a pipe 81, and between passage 76 and said cylinder by a passage 82 formed in the latter, the fluid being admitted into the opposite ends of the cylinder as shown in Fig. 3. Rod 80 is supported by a bracket 83 attached to said cylinder and is provided at its outer end with a handle 84.

To raise or lower the turn-table and the several mechanisms mounted thereon, there is provided the jack G. This mechanism includes, in addition to the cylinder 8, (upon the flange 9 of which the turn-table rests, as already stated) a solid vertical piston 85 which is formed as an integral part of a casting 86 rigidly secured to platform 1. The upper end of said piston terminates short of that of the cylinder 8, thereby providing a fluid-receiving chamber 87 (see Fig. 4). The fluid for operating the jack may be either air or water, the latter being considered preferable.

Upon the turn-table, and adjacent to the vertical cylinder 88, there is mounted an air-tight closed tank 88, through the upper end of which project two pipes 89 and 90. Pipe 89 opens at its upper end into pipe 24 (see Figs. 4 and 5) and extends only a very short distance into the tank. Pipe 90 extends close to the bottom of the tank and is in communication at its upper end with chamber 87 by way of a separate pipe 91 having a valve 92 arranged therein. Said pipe 90 is provided adjacent its upper end with a lateral branch 98 connected by a hose-pipe 99 with a pipe 100 arranged parallel with pipe 26 and having at its outer end a valve 101. Pipe 100 is adapted to be connected with one of the stand-pipes 30 when the tank is to be filled, such connection being possible either by means of a separate hose pipe 102 or by the detachable hose pipe 27, according as circumstances may require.

When the jack is to be operated hydraulically (it being understood that the tank has previously been filled with water to the desired level, which is below the end of pipe 89, and that air has been introduced into the upper portion of the tank) it is only necessary to open valve 92, whereupon the pressure of the air will force the water upwardly through pipe 90 into pipe 91 and thence into chamber 87. The water entering said chamber will gradually force cylinder 8 upwardly, the cylinder carrying with it the

turn-table and the mechanisms mounted upon the latter. When the required height has been reached, valve 92 is closed, whereupon said table will be retained in adjusted position. If the air stored within the tank be under high pressure, it will of itself be sufficient to operate the jack as above described; otherwise, it will be necessary to introduce an additional quantity of air into the tank through pipes 25, 24 and 89. It will be apparent, however, that the jack may be operated pneumatically, when the tank is empty of water by introducing air thereinto, as before, the air entering chamber 87 by way of pipes 90 and 91. In this connection, it may be stated that the principal object of raising the beam bodily is to permit it to be employed for leveling the coal in the ovens, as hereinafter described.

From the foregoing, it will be apparent that through the medium of the various mechanisms above described, the beam cylinder may be raised and lowered bodily, and swung or rocked either to the right or left by correspondingly moving the turn-table, and may be tilted in a vertical plane by operating lever 33. The operation of this lever also effects the reciprocation of the beam. Hence it is possible to so adjust the beam with reference to the oven that the shovel or other tool attached to the beam may reach any desired point in the oven when the beam is in operation. It will also be apparent that both controlling valves 31 and 43 are actuated by manipulating handle 33.

The machine as a whole is propelled along the track B by the traction mechanism H. This mechanism, which is best illustrated in Fig. 3, comprises a cylinder 103 pivotally supported at its rear end by means of trunnions 104 fitting in a bearing bracket 105 connected to the rear axle 3. The forward end of this cylinder may be adjustably supported by any preferred devices, such for instance, as that shown in the above-mentioned figure. In the present instance the front portion of the beam rests in a yoke 106 suspended by means of a chain 101 or similar device from one arm of an angle lever 102 pivoted in a depending bracket 103 secured to the under face of the platform. The other arm of this lever is connected by a rod 104 to an operating lever 105 located adjacent the lever 109. Levers 105 and 109 project through slots formed in said platform. Within said cylinder works a piston 106, the rod 107 of which is provided at its projecting outer end with a grab hook 108 designed for successive engagement with pins 109 carried by brackets 110 secured at proper intervals apart to the track ties 111, the pins being arranged longitudinally of the ties. The operating fluid

85

90

95

100

105

110

115

120

125

130

is supplied from pipe 26 to a valve chest 112 mounted on cylinder 103 by way of a hose-pipe 113, within which chest there is arranged a slide valve 114 similar to the valves already described. This valve controls the exhaust passage 115 and inlet passages 116 and 117 formed in the bottom wall of the chest, and is connected by means of a rod 118 to an operating lever 119 pivoted to a block 120 fastened to the traction cylinder. Connection is had between the inlet passages 116 and 117 and the ends of the traction cylinder by means of pipes 121 and 122.

15 In operating the traction mechanism to effect a forward movement of the machine, fluid is admitted through pipe 121 against the rear face of piston 106 so as to project the same outwardly until its hook is above the nearest pin 109. When such position is reached, the cylinder is lowered so as to engage the hook with said pin. The fluid is then admitted upon the opposite side of the piston, thereby retracting the latter and consequently causing the machine to advance along the track. The above operations are, of course, reversed when backward movement of the machine is desired. A definite relation exists between the positions of the pins and ovens, as will be understood, the machine being drawn into operative position when the piston reaches the limit of its inward movement. The traction mechanism is also operated to effect a slight forward and backward movement of the machine adjacent the mouth of an oven, to enable the shovel to reach various parts thereof.

The shovel which is employed in drawing the coke, is attached to the outer end of the beam, as shown in Figs. 6 to 10, wherein it is generally designated by the letter K. It consists of a head 123 formed with a passage in which the reduced terminal 124 of the beam fits, an upper jaw 125 rigidly secured to the head, and a lower jaw 126 pivotally connected to said head and having a further connection by means of a link 127 with a sleeve 128 slidable upon the beam. The beam terminal 124 has the outer end portion thereof threaded for engagement with a nut 129 which serves to retain the shovel or other tool in place. The upper jaw 125 is in the nature of a U-shaped skeleton frame, the front portion of which is formed with a series of rearwardly and downwardly inclined teeth 130. The lower jaw 126 comprises an angularly offset plate having a series of forwardly projecting teeth 131 secured to its front or lower edge, and a pair 60 of relatively short guard or stop teeth 132 secured to its side edges above and parallel with teeth 131. Upon the upper surface of the head and adjacent the rear end thereof, there is pivoted a trigger 133 having a nose 65 134 which is arranged for normal reception

in a seat 135 formed in sleeve 128. The trigger is formed with an upwardly extending trip arm 136 which lies in the path of a trip 137 pivoted to the forward end of a rod 138 which in turn is secured to a bar 139 mounted upon the forward end of the beam cylinder and projecting beyond the same. Bar 139 carries a depending hanger 140 wherein is mounted one above the other a pair of rollers 141 between which the beam slides and is supported. The teeth 132, above referred to, serve to arrest the movement of the blocks of coke onto the shovel and hold said blocks in place thereon.

During the operation of the shovel, its parts assume three positions which are illustrated in Figs. 7, 8 and 9. In the first position, the lower jaw of the shovel slides along the floor of the oven and is forced beneath the coke, the trigger 133 holding sleeve 128 against movement. When the shovel has been filled and is withdrawn from the oven, the friction of the lower jaw on the oven floor will cause said jaw to swing slightly upward, thereby sliding sleeve 128 toward the shovel head, as shown in Fig. 8, such action tilting the trigger upward by the engagement of the beveled face of its nose with the beveled rear wall of seat 135. When the shovel has been completely withdrawn from the oven, its trip arm 136 will come into contact with trip 137, whereupon the trigger arm will be raised still higher, thus freeing sleeve 128, which will slide rearwardly under the weight of the lower jaw and will in consequence discharge the load of coke on the ground in front of the oven. As the inward movement nears its limit, the sleeve will strike against bracket 140, and will be forced forwardly thereby until the trigger nose is reengaged in its seat, the trip 137 being swung upward on being struck by arm 136 so as not to interfere with such reengagement.

The shovel above described may be removed bodily, if desired, and replaced by the scraper head K' shown in Fig. 13. This element comprises merely two parts, namely, an attaching sleeve 142, which fits on the beam terminal 124 and is held in place thereon by nut 129, and a blade 143, said blade being similar in shape to that of an ordinary hoe. The scraper blade is designed to work upon the top of the caked mass of coke rather than beneath the same.

The scraper head is likewise replaceable by the leveling head K² which is shown in Fig. 14 and is adapted for use in leveling the coal in the oven before it has been burned into coke. Like the scraper head, it is composed of a sleeve 144 and a depending plate 145, the latter part being formed at its lower edge with a lateral flange 146 which extends the entire length of said plate and projects upon both sides thereof.

The machine finally includes a water brake which acts in conjunction with the hollow inner or supplemental piston 12 arranged within the main or beam cylinder 4 and is operated by water under pressure stored in tank 88. To supply water to said piston there is provided a pipe 147 arranged adjacent to pipe 22, (see Figs. 4 and 4^a) one end of this pipe opening directly into piston rod 14 while the other end is connected by a short hose pipe 148 with the upper end of pipe 90. Pipe 147, adjacent its outer end, is provided with a by-pass 149 having a valve 150 arranged therein, there being also 5 a controlling valve 151 and a drain or relief valve 152 arranged in pipe 147 to the left of the by-pass, and a check valve 153 arranged in said pipe between the arms of the by-pass. The check valve is adapted to 10 open when water is supplied to piston rod 14 and to close when such supply is completed, thus causing the water on exhausting, to return to the tank by way of the by-pass, the 15 passage of the water therethrough being controlled by the valve 150. On being admitted into the inner piston, the water will flow through the opening in the head 16 and will fill that portion of the hollow outer piston rod 13 to the left of the head. The 20 incoming water may, if desired, be utilized to project the main piston, (*i. e.* the beam) outwardly of its cylinder, and this is preferably the case when the scraper head is in use, since that tool must be placed with 25 considerable nicety upon the top of the coke. The main function of this water, however, is to act as a brake for the inward or return movement of the beam by checking the rapidity of such movement when effected by 30 air or steam, the water flowing through the by-pass during its return to the tank, the rapidity of such flow being controlled by valve 150, as above stated. There is also 35 included in the supply pipe 17 a by-pass 154 provided with a controlling valve 155, said pipe 17 being further provided with controlling and relief valves 156 and 157, and with a check-valve 158, the last-mentioned 40 valve being arranged between the arms of by-pass 154. This by-pass is active only during the exhaust movement of the actuating fluid which is directed therethrough by the action of the check-valve 158, which 45 valve acts in the same manner as the valve 150 in the water by-pass 149. When water pressure is not utilized, and the beam is actuated solely by air, the controlling valve 151 is closed, and at the same time the relief valve 152 is opened to prevent back 50 pressure of the air caused by the inner piston head 16. On the other hand, when the outward movement of the beam is effected by hydraulic pressure, valve 156 is closed and valve 157 opened. 55

The operation of the machine as a whole

is thought to be apparent from the foregoing, and further description thereof is accordingly omitted.

I claim as my invention:

1. In a machine of the type specified, a platform, a lifting jack mounted thereon, a beam pivotally mounted on said jack, means for supplying an actuating fluid to said jack to bodily raise the beam, and separate fluid-actuated mechanism for tilting said beam; 75 in combination with mechanism for reciprocating said beam.

2. In a machine of the type specified, a platform, a fluid-actuated jack mounted thereon, a beam pivotally connected with 80 said jack and raised and lowered by the operation thereof, a turn-table carried by the movable member of the jack, and fluid-actuated mechanism connected with the turn-table for operating the same to swing said 85 beam laterally; in combination with mechanism for reciprocating said beam.

3. In a machine of the type specified, a platform, a fluid-actuated jack mounted thereon, a beam pivotally connected with 90 said jack and raised and lowered by the operation thereof, a turn-table carried by the movable member of the jack, fluid-actuated mechanism connected with the turn-table for operating the same, to swing said beam 95 laterally, and additional fluid-actuated mechanism connected to said beam to tilt the same in a vertical plane; in combination with mechanism for reciprocating said beam.

4. In a coke-treating machine, the combination of a reciprocatory beam; a tool attached to the outer end thereof and comprising a fixed upper jaw and a movable lower jaw arranged to receive the coke between them, the second-named jaw being 105 adapted to support the coke; means for holding said second-named jaw rigid during movement of the beam in one direction; and means for releasing the holding means upon movement of said beam in the opposite direction, to liberate said second-named 110 jaw and dump the coke therefrom.

5. In a coke-treating machine, the combination of a reciprocatory beam; a tool attached to the outer end thereof and comprising a fixed upper jaw and a movable lower jaw arranged to receive the coke between them, the second-named jaw being adapted to support the coke; a trip member for holding the second-named jaw rigid 115 during movement of the beam in one direction; and means for tripping said member when said beam moves in the opposite direction, to liberate said second-named jaw and dump the coke therefrom. 120

6. In a coke-treating machine, the combination of a reciprocatory beam; a tool attached to the outer end thereof and comprising a fixed upper jaw and a movable lower jaw arranged to receive the coke be- 125 130

6
tween them, the second-named jaw being adapted to support the coke; a member slideable upon the beam and connected with the second-named jaw; means arranged for normal engagement with said member for holding the latter against movement, and said second-named jaw rigid during movement of the beam in one direction; and means for disengaging said holding means from said member when said beam moves in the opposite direction, to liberate said second-named jaw and dump the coke therefrom.

7. In a coke-treating machine, the combination of a reciprocatory beam; a tool attached to the outer end thereof and comprising a fixed upper jaw and a movable lower jaw arranged to receive the coke between them, the second-named jaw being adapted to support the coke; a member slideable upon the beam and connected with the second-named jaw; means arranged for normal engagement with said member for holding the latter against movement, and said second-named jaw rigid during movement of the beam in one direction; means for disengaging the holding means from said member upon movement of said beam in the opposite direction, to liberate said second-named jaw and dump the coke therefrom; and means for reengaging said member and holding means upon the termination of the second-named movement of the beam.

8. In a coke-treating machine, the combination of a reciprocatory beam; a tool attached to the outer end thereof and comprising a head, and fixed and movable jaws connected to said head; a collar slideable on the beam and connected with the second-named jaw; a trigger carried by said head and normally engaged with said collar, to hold the latter against movement, and said second-named jaw rigid during movement of the beam in one direction; and a trip arranged to operate said trigger when said beam moves in the opposite direction, to disengage the collar and liberate said second-named jaw.

9. In a coke-treating machine, the combination of a reciprocatory beam; a tool attached to the outer end thereof and comprising a head, and a fixed upper jaw and a movable lower jaw connected thereto, said jaws being arranged to receive the coke between them, and the second-named jaw to support the coke; a collar slideable on the beam and connected with said second-named jaw; a trigger carried by said head and normally engaged with said collar, to hold the latter against movement, and the second-named jaw rigid during movement of the beam in one direction; and a trip arranged to operate said trigger when said beam moves in the opposite direction, to disengage the collar and liberate the second-named jaw, for dumping the coke from the latter.

10. In a coke-treating machine, the com-

bination of a reciprocatory beam; a tool attached to the outer end thereof and comprising fixed and movable jaws; a collar slideable on the beam and connected with the second-named jaw; a member normally engaged with said collar for holding the latter against movement, and said second-named jaw rigid during movement of the beam in one direction; means for disengaging said member from said collar when the beam moves in the opposite direction, to liberate the second-named jaw; and a stop against which said collar is arranged to strike at the termination of the second-named movement of the beam, to shift the collar into reengagement with said member.

11. In a coke-treating machine, the combination of a cylinder and means for supporting the same, a fluid-actuated beam movable within the cylinder, a pipe-line for supplying the fluid to said cylinder, a by-pass located in said pipe-line, means for diverting the fluid into the by-pass during its movement in one direction, and means for controlling the passage of the fluid through said by-pass.

12. In a coke-treating machine, the combination of a beam, mechanism for imparting a reciprocatory movement thereto, mechanism for swinging the beam, separate devices for controlling the operation of said mechanisms, connections between said devices for causing their operation in unison, and an operating member connected to one of said devices.

13. In a coke-treating machine, the combination of a cylinder, a fluid-actuated beam movable therewithin, a second cylinder, a fluid-actuated piston movable within the same and connected to the first cylinder for tilting the same, a valve chest attached to each cylinder for controlling the supply of fluid thereto, a valve slideable in each chest, an operating rod connected to each valve, connections between said rods for causing their operation in unison, and an operating member connected to one rod.

14. In a machine of the type specified, the combination of a platform, a turn-table mounted thereon, a reciprocatory beam supported above said table, mechanism for bodily elevating said table and beam, and mechanism mounted upon said table and connected with said beam for tilting the same.

15. In a machine of the type specified, the combination of a platform, a turn-table mounted thereon, a reciprocatory beam supported above said table, mechanism for bodily elevating said table and beam, and mechanism mounted upon said platform and connected to said table for turning the same and said beam.

16. In a machine of the type specified, the combination of a platform, a turn-table

mounted thereon, a reciprocatory beam pivotally supported above the table, mechanism for bodily elevating said table and beam, mechanism mounted upon said platform and 5 connected to the table, for turning the same and said beam, and mechanism mounted upon said table and connected with said beam for tilting the same.

17. In a machine of the type specified, a 10 pivotally-mounted beam, fluid-actuated mechanism for bodily raising and lowering the beam, and fluid-actuated mechanism for swinging said beam; in combination with mechanism for reciprocating said beam.

18. In a machine of the type specified, a 15 pivotally-mounted beam, independent mechanism for swinging the beam in vertical and horizontal planes, and fluid-actuated mechanism for bodily raising and lowering said beam; in combination with mechanism for reciprocating said beam.

19. In a machine of the type specified, a 20 pivotally-mounted beam, independent, fluid-actuated mechanisms for swinging the beam in vertical and horizontal planes, and fluid 25

actuated mechanism for bodily raising and lowering said beam; in combination with mechanism for reciprocating said beam.

20. In a machine of the type specified, a 30 platform, a turn-table mounted thereon, a beam mounted on the turn-table, and fluid-actuated mechanism connected with said turn-table for operating the same, to swing the beam laterally; in combination with mechanism for reciprocating said beam. 35

21. In a machine of the type specified, a turn-table mounted thereon and having a radial extension, a beam mounted on the turn-table, and fluid-actuated mechanism connected with said extension for operating 40 said turn-table, to swing the beam laterally; in combination with mechanism for reciprocating said beam.

In testimony whereof I have hereunto set my hand in presence of two subscribing witnesses. 45

ANDREW H. REEDER.
